SOAP DISH

Guy Vrignaud, Grenoble, France, assignor to Allibert
Exploitation Societe Anonyme, Puteaux, France

Filed Nov. 6, 1974, Ser. No. 521,483

Claims priority, application France May 6, 1974

Term of patent 14 years

Int. Cl. D23—02

U.S. Cl. D6—90

FIG 1

FIG 2

FIG 3

FIG 4

FIG 5

FIG 6

FIG. 1 is a perspective view of a soap dish showing my new design;

FIG. 2 is a top plan view thereof;

FIG. 3 is a bottom plan view thereof;

FIG. 4 is a front elevational view thereof;

FIG. 5 is an end elevational view thereof, the other end elevational view being identical; and

FIG. 6 is a rear elevational view thereof.

I claim:

The ornamental design for a soap dish, as shown and described.
